Attorney

UNITED STATES PATENT OFFICE

HENRY WILSON, OF QUINCY, ILLINOIS, ASSIGNOR TO THE THOMAS WHITE STOVE COMPANY, OF SAME PLACE.

GRATE.

SPECIFICATION forming part of Letters Patent No. 663,377, dated December 4, 1900.

Application filed June 7, 1900. Serial No. 19,415. (No model.)

To all whom it may concern:

Be it known that I, HENRY WILSON, a citizen of the United States, residing at Quincy, in the county of Adams, State of Illinois, have 5 invented certain new and useful Improvements in Grates, of which the following is a specification, reference being had therein to the accompanying drawings.

This invention relates to grates, and particularly to grates having a rotating bar and an oscillating dump-bar coöperating therewith.

The invention has for one object to provide an improved construction for supporting and retaining in position the dump-bar, which oscillates toward and from a rotating bar at one side thereof.

The invention has as a further object to improve the structure of frame or casting adapted to receive and contain the grate-bar and to permit a reciprocatory motion of the dumping-bar when it is desired to disengage the same from its holding means.

Other objects and advantages of the invention will hereinafter appear in the following description, and the novel features thereof will be particularly pointed out in the appended claims.

In the drawings, Figure 1 represents a plan 30 of the grate. Fig. 2 is a vertical section on the line 2 2 of Fig. 1, and Fig. 3 is a similar view on the line 3 3 of Fig. 1.

Like letters of reference indicate like parts throughout the several figures of the drawings.

The letter A designates the grate frame or rest, adapted to receive and contain a rotating grate-bar B and an oscillatory bar C. The frame A is provided with sockets A', within 40 which the extended pintles B' of the rotating bar B rest, and with a similar socket or bearing A² for the pintles C' of the oscillating dump-bar. The end C² of one of the pintles of this bar is adapted to receive a suitable 45 operating-handle. The back of the frame A is provided with the usual form of supporting-flange A³ and one end of said frame with the plate A⁴ extending beyond the ends of the grate-bars and over the extended pintles 50 thereof.

The rotating grate-bar B may be of any

desired construction; but a preferred form thereof is shown in the drawings, which consists of a cylinder B², having apertures B³ therein and radially-extending teeth B⁴, which 55 in their rotation toward the dump-grate C clear the fire of loose ashes and tend to break up cinders or clinkers, so that they will pass through the space allowed when the dumping-grate is held in a fixed position, which is 60 its normal relation to the rotating grate. This structure of grate prevents the warping thereof by excessive heating and forms a means for quickly clearing the fire, while the cylindrical form thereof feeds air to the same, and 65 thereby improves the draft.

The dumping bar or grate C extends longitudinally of the rotating grate-bar B and is preferably formed with apertures C² therein, which are beveled downwardly from the upper face of the grate, as clearly shown in Figs. 2 and 3, thus permitting a free discharge of any ashes which may rest upon the bar. This bar is supported at one end upon a flange or rest A⁵, upon which the lower surface of the 75 bar A is normally supported, while the opposite end of this bar C is held against downward rotary or oscillatory movement by means of the stop-lug C³, which rests against the wall A⁶ at one side of the journaling-socket A², 80 thus limiting the oscillatory movement of the dumping-bar and supporting the same at both ends. When it is desired to oscillate or dump this bar, the same is reciprocated longitudinally, which moves the end of the bar from 85 the rest A⁵ and the lug C³ from its contact with the wall A⁶, permitting the bar C to drop downward, as shown by dotted lines in Figs. 2 and 3, so that large clinkers or other ashes may be cleared from the grate. This operation can also be assisted by rotating the grate B when the oscillating grate is dumped. The reciprocation of the grate C in one direction may be limited by the lug A⁷.

The operation of the several parts will be 95 apparent from the foregoing description, from which it will be seen that if the clinkers are too large or hard to be ground into small particles by the projecting teeth of the cylinder said cylinder may be turned to a point which 100 will bring such clinkers into position upon the grate, which may then be dumped in con-

nection with the rotation of the grate B, thus removing from the fire-box any clinkers or other matter without dumping the body of fire above the same. Of course if it be desired to clean out the grate the dumping-section may be shifted into its lowered position and the grate B rotated so as to cover the contents of the fire-box downward into the ash-pit. It will therefore be seen that the grate C is mounted for both a reciprocatory and oscillatory movement either in connection with the rotating cylindrical grate or independent thereof, and the means herein shown by which said oscillatory grate is supported permit the same to be easily shifted for the purpose of dumping. When in its normal fixed position, the grate is held against any movement due to the operation of the rotating grate, which carries into contact with the grate C the ashes and grinds the same into small particles free to pass between the teeth B⁴ and the edge of the grate C into the ash-pit.

It will be obvious that changes may be made in the details of construction and configurations of the grate-bars and other features of structure without departing from the spirit of the invention as defined by the appended claims.

Having described my invention, what I claim is—

1. In a grate, the combination with a frame provided with a rotating grate-bar, of an oscillatory dump-bar mounted in said frame to be reciprocated longitudinally of said rotating bar, a support on the frame for engaging and supporting one end of said oscillatory bar when reciprocated in one direction, and a stop at the opposite end of said bar to engage said frame when the bar rests upon said support; substantially as specified.

2. In a grate, the combination with a framework having bearings therein, a rotating grate mounted in said bearings, an oscillatory grate mounted for reciprocation in said frame, a flange at one end of said frame upon which said oscillatory grate may rest, and a stop at the opposite end of said oscillatory grate adapted to engage said framework to prevent

sagging of the grate when one end rests upon said flange; substantially as specified.

3. In a grate, the combination with a framework having bearings therein, a rotating grate mounted in said bearings, an oscillatory grate mounted in said frame, a flange at one end of said frame upon which said oscillatory grate may rest, a stop at the opposite end of said oscillatory grate to prevent dumping of the same, a plate extending from the end of said grate next said stop and provided with an aperture to permit a reciprocatory and oscillatory movement of the stop; substantially as specified.

4. In a grate, the combination with a framework having bearings therein, a rotating grate mounted in said bearings, an oscillatory grate mounted in said frame, a flange at one end of said frame upon which said oscillatory grate may rest, a stop at the opposite end of said oscillatory grate to prevent dumping of the same, a plate extending from the end of said grate next said stop and provided with an aperture to permit a reciprocatory and oscillatory movement of the stop, and a lug at the opposite end of said frame to limit the reciprocatory movement of the oscillatory grate toward the same; substantially as specified.

5. In a grate, the combination with a framework provided with front and rear bearings, a rotating grate supported in the front bearings, an oscillating grate supported in the rear bearing and having upon one of its pinnacles a stop-lug adapted to engage the wall of one bearing and hold the grate against oscillation, and a flange carried by the frame and extending beneath the opposite end of said oscillating grate, whereby the reciprocation of said grate disengages the same from said flange and the stop-lug from the wall of the bearing to permit a dumping of said grate; substantially as specified.

In testimony whereof I affix my signature in presence of two witnesses.

HENRY WILSON.
